LOAD TRANSFERRING MACHINERY

James Franklin Maine, Cleveland, Ohio, assignor
to The Consolidated Iron-Steel Manufacturing
Company, Cleveland, Ohio, a corporation of
Ohio

Application May 25, 1937, Serial No. 144,697

21 Claims. (Cl. 214—38)

This invention relates to load transferring machinery, particularly to machinery for transferring loads from a loading station to a vehicle; or from a vehicle to a loading station; or from one vehicle or station to another.

In my co-pending application, Serial No. 52-356 filed November 30, 1935, for improvements in Loading apparatus, now Patent No. 2,093,388, I have illustrated and described an apparatus by which a load, for example, a formed load such as a pre-arranged pile of packages, boxes or other articles, may be loaded upon the bed of a truck or other vehicle without further manual handling thereof and without disturbing the form of the pile or the arrangement of the pieces thereof.

By the load transferring machinery of the present invention, a load on a loading platform or other station may be picked up and deposited on a vehicle bed; or may be picked up from a vehicle bed and deposited at a receiving station; or may be loaded directly upon the transferring machinery and deposited either upon a receiving station or upon a vehicle bed; or may be picked up from one station or one vehicle and deposited upon another; and in the case of formed loads such as a pile of packages which are pre-arranged, the transfer in either case may be accomplished without disturbing the load or the arrangement of the pieces thereof.

My invention will be described in connection with the loading or unloading of a vehicle of the automotive type (among other uses) but it will be understood that it may be used with other types of vehicles, such for example as railway cars.

Among the objects of the invention are:

To provide an improved material transferring apparatus;

To provide an improved transfer apparatus for moving loads composed of pieces disposed in a pre-arranged order, from one place to another, without disturbing the arrangement of the pieces;

To provide machinery for picking up loads of articles and for discharging them, having an improved mode of operation;

To provide an improved material handling apparatus which will pick up a load from a loading platform or other station and deposit it upon a vehicle bed; or will pick up a load from a vehicle bed and transfer it to a receiving station; or will transfer to a receiving station or vehicle bed a load which has been placed on the apparatus; or will pick up a load from one station or vehicle and deposit it upon another; the apparatus oper-

ating, in either of the said modes of operation, in an improved manner.

Other objects will be apparent to those skilled in the art to which my invention appertains.

My invention is fully disclosed in the following description taken in connection with the accompanying drawings in which:

Fig. 1 is a side elevational view of an apparatus embodying my invention;

Figs. 2, 3 and 4 are side elevational views of the embodiment of Fig. 1 drawn to a smaller scale and in simplified form and showing three different positions which the apparatus of Fig. 1 may assume in different phases of its operation;

Fig. 5 is an end elevational, partly sectional view taken from the plane 5—5 of Fig. 1;

Fig. 6 is a view to a greatly enlarged scale of a part of Fig. 1, the parts however being illustrated in the operative position of Fig. 2;

Fig. 7 is a view similar to Fig. 6 of another part of the apparatus of Fig. 1 in the same operative position;

Fig. 8 is a top plan view of a part of the apparatus of Fig. 1 drawn to a larger scale;

Fig. 9 is an end elevational view with parts broken away and to a larger scale of a truck, forming part of the apparatus of Fig. 1;

Fig. 10 is a top plan view with parts broken away of the truck of Fig. 9, the view being taken approximately in the direction of the arrow 10 of Fig. 9;

Fig. 11 is a view similar to a part of Fig. 1, drawn to a larger scale and illustrating a part of the mechanism of the truck of Fig. 9, the parts all being drawn to a larger scale and showing in detail a locking mechanism which may be employed;

Fig. 12 is a view similar to a part of Fig. 11, illustrating the corresponding parts thereof at the opposite end portion of the embodiment of Fig. 1 and illustrating mechanism parts thereof in different positions from that which they assume in Fig. 11;

Fig. 13 is a sectional view taken approximately from the plane 13—13 of Fig. 11 and showing in solid line, parts which are in Fig. 11 shown in broken line;

Fig. 14 is a fragmentary, sectional view taken from the plane 14—14 of Fig. 12;

Fig. 15 is a diagrammatic representation of an electric control system which may be utilized to operate circuit motors supplying power to various parts of the apparatus illustrated in the above figures;

Fig. 16 is an enlarged fragment of the diagram of Fig. 15;

Fig. 17 is a fragmentary view similar to a part of Fig. 6 near the right hand end thereof illustrating a modification which may be employed;

Fig. 18 is a fragmentary sectional view taken from the plane 18-18 of Fig. 17.

Referring to the drawings, I have shown generally at 1 a frame preferably built up from

- 10 rolled steel sections, comprising transverse beams 2-2 thereunder adjacent each end thereof; longitudinal frame members 3-3 resting on the beams 2; a pair of upright channel posts 4-4 at one end of the frame (the right end, as viewed in Fig. 1) a corresponding pair of uprights 5-5 at the opposite end of the frame; one or more transverse frame members 6, secured to the uprights; a pair of laterally spaced longitudinally extending channel form rails 7-7; upper longitudinal frame members 8-8 and various brace members 9-9. On each side of the frame is a pair of flanged wheels 10-10, four wheels in all, rotatably supported in bearings 11-11 on the beams 2-2, the pairs of wheels 10-10 at the 25 end of the frame rolling on rails 12-12.

To propel the frame along the rails 12-12, the axles of the wheels 10-10 on one side of the frame have gears 13-13 connected thereto meshing with pinions 14-14 on a driving shaft 30 15 supported in bearings on the underside of the longitudinal frame members 3 and having a gear 16 thereon meshing with a pinion 17 driven by a motor 18 supported on the frame.

By this means when the motor 18 is energized 35 to rotate it in one direction, the frame 1 will be propelled along the rails 12 in one direction and by reversing the motor, the frame may be reversely propelled.

Illustrated generally at 19 (see Figs. 1 and 5) 40 is a load body or skid comprising side walls 20-20 preferably formed from sheet metal and braced by side ribs 21-21; and having a sheet metal bottom 22; the bottom and sides being supported upon longitudinally extending corner 45 angles 23-23; and transverse members 29 of T-section connecting the corner angle.

A plurality of rollers 24-24 extend transversely of the skid adjacent the bottom thereof and relatively close together as shown in Figs. 50 1 and 8.

The rollers 24-24 in parallel relation are rotatably mounted on the skid. The preferred means is to rotatably support them on shafts 25-25 extending longitudinally through the rollers and secured in the corner angles 23 at opposite ends thereof.

An endless belt 26 is looped over end rollers 27 and 28, both of which are indicated in Figs. 1, 6, 7 and 8, the upper flight of the belt therefore 60 resting upon the upper sides of the rollers 24 and the other flight being thereunder.

To drive the upper belt flight for purposes to be described, the end roller 27 and the roller 24 next adjacent thereto have sprocket wheels 30 and 31 respectively secured thereto and connected by a sprocket chain 32. The said roller 24 is rigidly connected to a shaft (instead of rotating on a shaft 25 as in the case of the other rollers) which has rotary bearing in end castings 34-34 bolted to the corner angles 23-23 and projects therethrough and has mounted thereon exteriorly thereof a sprocket wheel 36.

As will now be apparent, if the sprocket wheel 36 is driven, the sprocket wheel 31 will drive the sprocket wheel 30 which, in turn, will drive the

end roller 27 and it will propel the belt, causing the upper flight 26 thereof to move either toward the right or toward the left as viewed in Fig. 1 depending upon the direction of the application of power.

To thus drive the sprocket wheel 36, a motor 37 is mounted on a suitable bracket on the outside of the skid 19 and by means of speed reduction gears (not shown) in a gear housing 38, drives, at relatively low speed, a sprocket wheel 10 39 which is connected by a sprocket chain 40 with the said sprocket wheel 36. To this end also the end roller 27 is mounted upon a shaft 41 rotatable in bearings in the end castings 34-34.

The opposite end roller 28 is similarly mounted on a shaft 42 which rotates in bearings 42A in sliding heads 43-43 slidable longitudinally in boxes 44-44 secured to the corner angles 23-23; and means is provided to tension the belt between the two end pulleys comprising bolts 45-45 threaded each in a lug 46 on one of the corner angles 23 and seated in sockets 47 in the sliding heads 43. By turning the bolts 45, the heads 43 will be moved to tension the belt, and to equalize the tension from side to side thereof, as will be understood.

Each end of the skid 19 is normally supported by a pair of wheels 48-48 normally resting upon flat portions 49-49 of trackways 50-50 at each end of the main frame 1 having also inclined trackway portions 51-51, see Fig. 1. The wheels 48-48 are mounted upon the opposite ends of shafts 52-52 which extend across the skid preferably between the belt flights and rotate in bearings 53-53 in castings 54-54 secured to the corner angles 23-23.

As will hereinafter be described, the wheels 48-48 are normally stopped by abutments to cause them to remain on the flat portion 49 of the trackways 50 but when one end of the skid 19 is otherwise supported, the wheels 48-48 of the other end may roll down the inclined portions 51-51 of the trackways 50-50.

The extreme ends of the skid 19 are provided with supporting rollers and an apron, the construction at both ends being substantially the same and one end will now be described.

Shafts 55-55 extend across the skid beyond and adjacent to the end loops of the belt, one 50 shaft (that on the right end as viewed in Fig. 1) being rotatably mounted in bearings 56-56 in the end casting 34 and the other shaft being mounted in bearings 57-57 secured to the corner angles. 55 Rollers 58-58 are mounted on the ends of the shafts and their lowered sides project below the lowest parts of the end portions of the skid. When the end of the skid rests upon a vehicle bed, loading or receiving platform, etc., as will 60 be described in connection with the operation as a whole, the end of the skid will be supported by the rollers 58-58.

On the shaft 55 is a plurality of rollers 59-59 which turn on the shaft. An apron shown generally at 61 is provided, formed from sheet metal and comprising a nose 62 and an upwardly rearwardly inclined portion 63. The nose is bent under as at 64 and has mounted thereon a plurality of apron rollers 65-65 extending in a line transversely across the skid, under the inclined portion 63. The inclined portion 63 is notched out to provide tongue portions 66-66 which extend between the rollers 59-59 and are bent around the shaft 55 whereby the entire apron may oscil- 75

late around the shaft and be supported thereby at the rearward portion of the apron.

Intermediate the apron rollers 65, is a transverse series of rollers 67-67 hereinafter referred to as load rollers rotatably mounted on the underside of the inclined portion 63 of the apron and having the upper sides thereof extending upwardly above the apron surface through perforations in the inclined part of the apron, the purpose of which will hereinafter appear in connection with a description of the whole.

The end casting 34 is preferably provided with a sheet metal buffer 69 secured thereto having a vertical edge 70 in a plane slightly in advance 15 of the nose 62 of the apron and when viewed from above, flaring out laterally as shown at 71, Figs. 8 and 18. The form of this buffer thus tends to guide a load into the skid as will appear later.

20 Illustrated generally at 72 is a truck, supported by wheels 85-85 on the rails 7-7 and driven therealong in a manner to be described.

The general operation of the skid 19 as thus far described will now be given in connection 25 with the truck 72 and a detailed description of the truck 72 will follow later.

The rails 12-12 are preferably located adjacent to a loading or receiving platform 73 and it will be assumed that it is desired to transfer 30 a pile of packages 74 which are on the platform 73, to the bed 75 of a vehicle. The general arrangement of the parts, in this instance, is that illustrated in Fig. 4. The truck 72 is now operated to raise the end of the skid, the left end 35 as viewed in Figs. 1 and 4, so that the wheels 48 at that end of the skid are raised from the trackway 50 and supported on the truck. The other end of the skid being supported by the wheels 48 at that end resting on the trackways 40 51. The truck 72 is then operated to move it bodily along the rails 7-7 carrying its end of 45 the skid with it. The wheels 48 on the other end of the skid thereupon roll down the inclines 51-51 of the trackways 50-50 which lowers the roller wheels 58-58 down upon the platform 73.

In the preferred practice of my invention, the load 74, particularly when it consists of a pre-arranged pile of packages is piled on the platform 73 upon a piece of carpet or other like 50 flexible material 187 shown in its normal position at 76, Fig. 4. The farther end of the carpet is secured to the platform as at 188. When the roller wheels 58 are resting upon the platform 73, further movement of the truck 72 may be stopped, 55 momentarily, and the free end of the carpet 76 may be laid upon the apron 61, over and resting upon the upper sides of the load rollers 67 and the free end placed over the rollers 59-59 and 60 downwardly behind and under the end of the belt on the end roller 27.

The rearward movement of the truck above mentioned may now be continued and simultaneously therewith the motor 37 may be energized to move the upper belt flight forwardly, that is to say in the direction opposite to the rearward movement of the skid 19 and the apron 61 thereof. The apron now, so to speak, plows its way under the carpet 76 and when the pile 70 of packages 74 is reached, it lifts them progressively from the forward end to the rearward end of the pile, the carpet rolling freely over the load rollers 67 and the rollers 59, and when the packages have successively passed over the rollers 59 they engage the end of the travelling belt

26 which carries them forwardly into the skid 19 between the walls thereof. This continues until the apron 61 has reached the rear end of the pile and the last packages of the pile have been transferred to the belt in the skid. A continuing forward movement of the belt alone will place the packages midway longitudinally of the skid, if desired, at this time.

At this time then, the truck 72 is operated to move back to its original position on the rails 10 7-7 during which movement the skid is withdrawn from the carpet 187, and the latter by being attached to the platform is ready to have another load of packages piled thereon. The truck 72, after it reaches its end or original position, is operated to lower the skid end again upon the trackway 50. The truck 72 is then moved freely to the other end of its rails 7-7 and is operated to engage the right hand end of the skid and to elevate it above the trackways 20 50-50 supporting it now on the truck itself. The truck is then operated to move toward the left whereupon the wheels 48-48 at the left end of the skid roll down the inclines 51-51 of the trackways 50-50 which deposits the roller wheels 25 58-58 upon the bed of the vehicle. Continuing movement of the truck will roll the forward end of the skid over the vehicle bed until it is adjacent the cab 77 thereof and then its motion is stopped. The truck 72 is then reversed and 30 moves backward along its rails carrying the supported skid end with it and simultaneously therewith, the belt is propelled by the motor 37 forwardly which deposits the packages upon the bed of the vehicle. This completes the cycle of 35 operations, except that the truck 72 which is now at the rear of the main frame is operated to lower the skid upon the trackways 50-50 and to then freely return to the forward end of the frame for other operations.

40 In a similar manner, if a vehicle load of articles is to be transferred to the station 73, the truck 72 is first moved to the rear of the frame and elevates that end of the skid and then is operated to move toward the left, moving the 45 forward end of the skid onto the vehicle bed, the apron lifting the articles and the belt conveying them backward into the skid; and then the truck 72 is returned to the rear and lowers the rear end of the skid on the frame. The 50 truck 72 is then moved to the forward end of the frame and elevates the forward end of the skid and then moves to the rearward end of the frame carrying the forward end of the skid with it and moving the rear end of the skid onto 55 the platform; it then withdraws the skid forwardly and the belt floor moves rearwardly which leaves the load on the platform. The operation is the same as that described above except that the station is replaced by the vehicle and the 60 vehicle is replaced by the station. In such cases, of course, it is preferable that the vehicle bed 75 has thereon a piece of carpet or the like upon which the load is placed, at the point at which it was loaded, such carpet being secured to the 65 truck by being secured to the bed at the forward part thereof.

70 In another mode of operation, the articles may be loaded by hand into the skid while in its normal position on the frame and then when the vehicle is brought to the station, they may be loaded into the vehicle by moving the skid forwardly into the vehicle and then withdrawing it and advancing the upper flight of the belt simultaneously as above described. Again, in 75

any case, whenever a load is in the skid, whether being placed there by hand or having been operationally loaded thereinto from a vehicle or from one point of a station, it can be moved along the rails 12-12 to another vehicle or to another station and loaded into either.

As shown in Figs. 2 to 4, the skid may pivot upon the truck 72, the end of the skid opposite the truck therefore being movable vertically up and down. When the end of the skid, as in Fig. 2, rolls down the trackway 51, and the wheels 58 are thereby lowered upon the platform or station 73, the wheels 48 will clear the trackway 51, and the platform 73 and this will be true for various heights of platforms, the inclination and length of the trackway 51 automatically compensating for different heights of platform without further adjusting means.

Furthermore, when the other end of the skid is moved as described toward the vehicle, see Fig. 3, and the wheels 48 roll down the inclined trackway 51 and deposit the roller wheels 58 upon the bed of the vehicle, rolling engagement with the bed will be effected for different heights of vehicle beds; and in this case also, although the bed of any given vehicle may be relatively high when unloaded and gradually descends as the load is transferred thereto, the pivoting of the skid around the truck 72 will not only initially cause the rollers 58 to engage the bed in the first instance but will maintain them in rolling engagement with the bed as it changes its height; and as just described for the other end of the apparatus, no further adjustment or compensating means other than the length and inclination of the trackway on which the wheels 48 roll is needed.

While as described above, the preferred mode of operation involves a piece of carpet or the like attached to the station and another attached to the vehicle bed, the apparatus may operate equally well if the piece of carpet goes with the load. In such cases, the load 74 would be piled upon a piece of carpet 76, say at a station 73 and when the skid apron plows under the carpet to transfer the load to the skid, the free end of the carpet may be allowed to travel upwardly over the rollers and into the skid on the belt flight so that when the load has been transferred to the skid, the carpet will be under the load between the load and the upper flight of the belt.

Then when the apparatus is operated to transfer the load to the vehicle bed, the carpet will be transferred with it and lie between the load and the vehicle bed.

Unloading in such a case from the truck will be the same, in general, as unloading from the station and the carpet will travel back into the skid and be delivered again under the load to and upon the station platform.

There are many cases in which the carpet is not essential at all. This will be true when the nature of the packages will permit the apron 61 to slide or plow thereunder without the help of the carpet and is particularly true when the load is placed by hand in the skid and is not loaded thereinto by the apparatus but is only unloaded therefrom, it being clear that the apron can be dispensed with when the skid discharges a load by its movement of the upper belt flight toward the load and the withdrawal of the skid and the belt as a whole from under the load.

As will become more apparent from the elec-

tric control system proposed for operating the motor 37 and the motor which operates the truck 72 to move it along the rails 1-1, the speed at which the upper flight of the belt moves may be regulated relative to that at which the truck 72 moves the skid as a whole. For example, when as above described in connection with Fig. 2, the skid is moving toward the load 74 and the upper part of the belt is moving in the other direction to transfer the load from the platform to the belt in the skid, the belt may be caused to run not at the same forward speed as the skid is moving rearwardly but at a slightly lesser speed. By this means, the upper belt flight drags slightly in the rearward direction on the undersides of the undermost packages of the load thereon which, continuously packs the load and keeps it in order by exerting rearward pressure on the entire pile pressing it back against the wall 78, or against stanchions or the like which may be at the back of the pile. This action tends to maintain the pre-arranged order of the pile of packages and tends to prevent them from becoming displaced or loosened as a pile, while being loaded. Similarly, but in the reverse sense, when as indicated in Fig. 3, the upper belt flight is moving forwardly and the skid as a whole is moving rearwardly to deposit the packages on the vehicle, the belt flight is caused to move forwardly at a slightly greater velocity than the rearward movement of the skid so that again the belt flight drags on the under side of the undermost packages of the pile and constantly exerts pressure to pack the load against the rear wall 79 of the cab 77, or against stanchions or the like disposed thereat, which maintains the pile solid and compact throughout the unloading process. This is of particular advantage when the load is to be unloaded from the vehicle bed by similar apparatus at another station.

Obviously, this same principle may be employed when a load is being unloaded from a vehicle bed instead of from a platform and when it is being delivered to a platform instead of to a vehicle.

The construction and detail operation of the truck 72 above referred to in general will now be described.

The truck (see Figs. 9 and 10) comprises a frame shown generally at 72 of which the principal elements are a pair of lateral channels 80-80, front and rear channels 81-81, transverse pairs of angles 82-82 and 83-83; and the usual bracing members. A pair of shafts 187-187 are mounted in bearings 84-84 on the frame and have mounted on their opposite ends pairs of flanged wheels, 85-85, four in all, these being the truck wheels referred to above, which run on the rails 1-1 forwardly and rearwardly of the main frame above referred to, carrying the frame of the truck with them.

To propel the wheels, one of the shafts 187 has a gear 86 thereon meshed with a pinion 87 driven through gear reduction means in a casing 88 by a motor 89 supported on the casing, the casing supported on the transverse angles 82-82. As will now be clear, by driving the motor 89, the wheels 85-85 will propel the truck forwardly or rearwardly along the rails 1-1.

The wheels 85-85 running on the rails 1-1 may have sprocket wheels 103-103 on the respective shafts 187-187 connected by sprocket chain 104 whereby the motor 89 may drive all of the wheels equally.

Mounted upon the transverse angles 83-83 is

5 a frame 90 extending upwardly therefrom on which is mounted a casing 91 containing gear reduction means and to which casing is connected a motor 92, the motor driving the gear reduction means, and the latter having a shaft 93 extending out of the casing driven by the motor.

10 At each end of the truck frame is a pair of upright angles 94—94 secured to which is a pair of cross angles 95—95, the latter supporting a plate 96 upon which is rotatably abutted one face of a rotatable nut 97 having a sprocket wheel 98 secured thereto. A screw 99 threaded through the nut projects downwardly through a perforation in the plate 96. On the aforesaid shaft 93 15 is a pair of sprocket wheels 100 and 101 and sprocket chains 102—102 connect the respective sprocket wheels 100 and 101 to the respective sprocket wheels 98—98 on the said screws 99—99.

20 As will now be apparent when the motor 92 is operated, the nuts 97—97 will be rotated in one direction or the other and the screws 99—99 25 propelled upwardly or downwardly.

The screws 99—99 are connected respectively 28 each to a plate 105 which is, in turn, connected to the ends of a pair of angle irons 106—106, the angle irons 106 constituting together with the plate 105 a beam, both ends of which move vertically uniformly with movement of the screws.

30 The upper ends of the upright angles 94 preferably overlap the outer sides of the angles 106—106 to guide the latter against shifting forwardly and rearwardly of the truck and preferably ears 107—107 on the ends of the angles 35 106—106 overlap the uprights 94 to guide the said beam against shifting transversely of the truck.

On the underside of the skid 19 adjacent each 40 end thereof is a plate 108 having a notch 109 therein. The above mentioned plate 105 at the upper end of the screw has a tongue 110 adapted to be projected into the notch. The tongue when 45 in the notch thus locks the skid 19 against transverse movement relative to the plate 105 by overlapping upwardly the corner angle 23 of the skid, and locks the skid against longitudinal movement by the engagement of the tongue with the notch.

50 Thus when, in a manner to be described, the screws are elevated to engage the plate 105 with the underside of the corner angles and therefore 55 with the underside of the skid, the skid is locked against shifting either longitudinally or laterally on the plate supporting it, and as will now be understood it is the elevation of the screws by which the skid is raised from its trackways 50—51 and supported on the truck 72 for the purposes above described. The raising and lowering of the skid by the screws 99—99 to transfer the skid from its own trackway support to the truck 72 being accomplished by energization of the motor 92.

60 The skid is furthermore locked to the said plate 105 when the screws are elevated to engage the skid by a latch 111 pivoted on a pin 112 supported upon the angles 106—106 and having a hook 113 at its upper end engageable with the upper side of the plate 108 on the skid when the said beams are raised; the latch being spring 65 pressed by a spring impelled pin 114 reacting at one end upon a connector 115 connecting the ends of the said angles 106—106 to join them into the said beam, and at the other end reacting on a cotter 116 extending through the pin 114, the pin 114 being guided in perforations in 70 a flange of the connector 115 and in a depending

lug 117 on the connector, and the inner end of the pin engaging a lug 118 on the latch 111.

The latch has also a lug 119 which when the said beam, and therefore the pivot pin 112 for the latch, is lowered engages the upper end of 5 a post 120 which rocks the hook 113 out of locking engagement to unlock the latch.

The truck 72 is provided with means for locking the wheels 48—48 upon the flat or horizontal portions 49 of the trackways 50—50 and for 10 unlocking them in the operation of the truck and this will now be described.

On the inside of the channel uprights 5—5 adjacent the upper ends thereof, a dog 121 is mounted reciprocable vertically through perforations 122 and 123 in the upper and lower flanges of the trackway 50, the upper extreme end of the dog having an inclined face 124. The dog 121 is normally retained in an upper position in which the upper end portion 125 including the 20 face 124 extends upwardly above the trackway, by a spring 126 surrounding a shank 127 of reduced diameter on the dog below the lower flange 128 of the trackway, the spring abutting at one end upon a shoulder 129 on the dog and at the 25 lower end abutting upon a bracket 130, into a perforation in which, the lower end of the shank 127 projects to guide the plunger. The dog 121 may be stopped in its upward position by the engagement of a washer 131 at the upper end of 30 the spring 126 with the underside of the flange 128 at the trackway.

Upon every occasion when the wheel 48 is rolled up the trackway 50 on the upper flange 132 thereof, (in the operation of the skid, as 35 above described, when the truck 72 returns the skid to its normal position on the main frame), the wheel encounters the face 124 of the dog 121 and pushes the dog downwardly. The dog has a tooth 133 which normally is engaged by a tooth 40 134 on an arm 135 pivoted at 136 on the bracket 130. The arm 135 is normally resiliently constrained to move clockwise as viewed in the drawing by a plunger 136 reciprocable in brackets 137 and 138 mounted on the trackway 50 and 45 engaging at its inner end a recess 139 in the side of the arm 135 and being resiliently thrust thereinto by a spring 140 abutting at one end upon a part of the bracket 138 and at the other end upon a collar 141 on the plunger 136 and being 50 guided in perforations 142—142 in the bracket. When therefore, as above described, the dog 121 is depressed by a wheel 48, the tooth 133 is moved downwardly out of engagement with the tooth 134 and the arm 135 is moved toward the right by the 55 plunger 136.

A lock element 143 is pivoted at 144 on the rail 50 and is provided with a notch 145, a camming surface 146, and a wheel engaging prong 147. The locking element 143 is normally retained by 60 gravity in a downward position in which the wheel engaging prong is below the upper edge of the flange 132 of the trackway 50. When however the arm 135 is moved clockwise, as described, the upper end thereof engaging the camming surface 146 rocks the locking element 65 counterclockwise projecting the wheel engaging prong 147 upwardly through a perforation 148 in the flange of the trackway, the end of the arm 135 thereupon moving into and being stopped in 70 the notch 145. The parts now take up the position shown in Fig. 12. The operation of the parts just described was effected by rolling of the wheel 48 inwardly along the trackway and the movement of the wheel is now stopped by its engage- 75

- ment with the prong 147, the latter being prevented from yielding by the arm 135 which, as shown, takes up by longitudinal thrust therein on its pivot 136, any force of the wheel 48 tending to rock the prong 147 out of its locked position. Thus upon each return of the skid, as above described, in the operation of the skid to its normal position, it is locked thereat at both ends thereof.
- 10 To disengage the lock, to permit the skid to be moved longitudinally by the truck, as above described, the following means is provided to rock the arm 135 counter-clockwise to disengage it from the locking element, and to retract the 15 plunger 136 and to permit the locking element prong to fall out of the path of the wheel 48. This means comprises a plunger 149 extending through a perforation 150 in the said bracket 137 and having its inner end seated in a recess 151 on the side of the arm 135 opposite the recess 139.
- As shown in Fig. 11, upon the truck frame, there are two plungers 149—149, one for release of the said lock at each end of the skid. The 20 plungers 149 are preferably aligned with each other and reciprocable in suitable perforations in a pair of flanges 152—152 supported on a cross flange 153, the inner end portions of the plungers being pivotally connected as at 154—154 to upright bell-crank arms 155—155 pivotally mounted in bearings on the lower side of the cross angle 153 as at 156. The other or horizontal bell-crank arms are pivotally connected, as at 157, to an extension 158 on the lower end of the 25 above described screw 99. By this means when the screw 99 is propelled upwardly, it rocks the upright bell-crank arms 155 to propel the plungers 149—149 outwardly and therefore in the direction to move the arm 135 above referred to 30 in the direction to unlock the locking element. It will be observed that the same upward movement of the screw which attached the latch 111 and locked the plate 105 to the skid, in effect locked the end of the skid to the truck so that 35 there is no longer need of the prong 147 locking the wheels 48 to the trackway at that end of the skid.
- Thus, supplementing the above description of the operations of the apparatus which was given 40 prior to the description of the truck itself, it may now be said that when the truck motor 92 is operated, the screws 99—99 are propelled upwardly to lock the end of the skid to the truck and to elevate the end of the skid from its trackway supports; then said motor is de-energized and the motor 89 is energized to propel the truck to 45 carry the end of the skid with it in the operation hereinbefore described. Each time that the skid is returned to its normal position over the main frame by the truck 72, the end which is not supported by the truck rolls up the inclined part 50 of the trackway 50 and by engaging the dog 121 thereat on its camming face 124, sets the locking element 143 to lock the wheels 48—48 at that end of the skid so that they cannot roll 55 inwardly on the trackways; further movement of the truck 72 is thereupon stopped. When the truck supported end of the skid is lowered by the truck mechanism, the wheels 48—48 descend upon the upper ends 125 of the dogs 121 and depress them, setting the locking elements 143 at that end of the skid; so that the skid is locked at both ends, locking it against movement in either direction. And as will now be clear, when 60 the truck is operated to raise the screws, it must

be in a predetermined position under the end portion of the skid whereat it will unlock there-with because at any other position longitudinally along the rails 7, it will not release the wheel lock and even if it should be inadvertently operated to raise the skid, it cannot move it longitudinally. Thus these operations are interlocked with each other, for safety and other obviously desired reasons.

To energize the motors 92 and 89 on the truck, 10 current may be led directly from supply mains to a pair of bus bars 160—161 extending longitudinally of the main frame 1, and shoes 162 and 163 on the truck 72 may pick up the current for the motors 92 and 89. But if, as preferred, the 15 traverse of the main frame on the rails 12—12 is employed, bus bars 164 and 165 may be provided under the loading platform 73 and shoes 166 and 167 on the frame may pick up current therefrom and supply it to the said bus bars 160 and 161. 20

It is deemed unnecessary herein to show the electric conductors on the apparatus by which the electric motors are energized and reversed but the electric circuits therefor are shown in Fig. 15 to which reference may now be made.

Electric current may be supplied to the belt motor 37 by the following means. A pair of contacts 168—168 and a pair of contacts 189—189 are provided on the skid end adjacent to each end thereof and the contacts 168—168 are engageable respectively by a pair of contacts 169—169 on the truck and the contacts 189—189 are engageable by a pair of contacts 190—190 each time that the plate 105 on the truck is elevated. The contacts 169—169 on the truck may 35 be connected to the said bus bar shoes and receive current therefrom through a reversing switch 174; and the contacts 168—168 on the skid may be connected by suitable conductors to the armature of the motor 37. The contacts 40 190—190 are connected to the shoes 162—163 and when they engage the contacts 189—189, they supply current to the motor field 176 through a rheostat 175. By this arrangement, the truck plate may be elevated at any time to 45 a point at which it will cause the said contacts to engage without actually raising the skid, whereby the belt of the skid may be propelled forwardly or backwardly to position a load thereon independently of truck movement and if the 50 truck plate 105 is elevated far enough to engage the skid bottom, the contacts will still be maintained engaged so that also after the end of the truck has been elevated, the belt may be propelled in either direction and the belt speed may 55 be controlled by the rheostat 175.

A platform 170 may be provided at any suitable place preferably on the truck 72 upon which an operator may stand and operate an electric controller to perform the above described motor 60 functions.

To position the main frame along the rails 12—12, a reversing switch 171 may be thrown in one direction or the other and the main frame traverse travel motor 18 will receive current from 65 the bus bars 160—161 and the shoes 162—163 thereon and bus bars 164—165 and the shoes 166—167 thereon. When the main frame is thus positioned at the desired station, the switch 171 is thrown to the open position. To operate the screws 99 to raise and lower the plates 105 into or out of engagement with the skid, a reversing switch 172 may be thrown in one direction or the other to operate the truck elevator motor 92 and when this has been done, the switch 172 may be 70 75

opened. Then to propel the skid along the frame, the reversing switch 173 may be thrown in one direction or the other depending upon which end of the main frame the truck 72 is at, to energize the truck travel motor 88 and when its travel is completed this switch may be opened.

Limit switches 177 and 178 may be provided in the circuit to the main frame travel motor 18 as indicated in Fig. 15 and Fig. 16; to prevent 10 overtravel of the frame on the rails 12-12; and limit switches 179 and 180 may be provided in the circuit to the truck travel motor to prevent overtravel thereof on the rails 7-7 as indicated in Fig. 1; and if desired, limit switches may be 15 provided for the elevator motor to limit the amount of elevation of the skid by that motor if desired, although not shown. The construction of such limit switches comprises no essential part 20 of the present invention and being well known in bridge-crane and other types of motor operated apparatus will be understood by those skilled in this art without further description or illustration. The limit switches 179 and 180 may 25 be set to stop the travel of the truck 72 at each end of its travel at a position at which it unlocks the wheel locks thereof and in a position at which the tongue 109 will engage the recess 110 on the skid and therefore such limit switches are made adjustable as shown in Fig. 16, wherein a 30 switch arm 181 is held in engagement with a contact 182 by a spring 183 and may be moved to disengage the contact by the travel of an element 184 of the truck in which is adjustably screw threaded a screw 185, the end of which abuts upon 35 the switch arm 181 at the end of the travel to operate it, as described.

Whereas I have illustrated the invention as having motors operated by a two-line, direct current circuit, it will be understood by those skilled 40 in the art that they may be alternating current motors and operated by alternating current.

If the skid 19 should be propelled bodily by the truck 72 unintentionally or by accident on an occasion when there was no station 73 or vehicle bed 75 to support the overhanging end of the skid, the wheels 48 would otherwise roll off of the ends of the trackway 51. To prevent such malfunctioning, a wheel 186 is mounted on suitable bearings at each corner of the main frame 50 and directly under the corner angles 23 of the skid, and the corner angles will descend upon said wheels when the wheels 48 leave the trackway 51 and therefore the wheels 186 will support the end of the skid.

It will be understood that the switches 171, 172 55 and 173 and 174 and the rheostat 175 may all be mounted on a suitable panel or embodied in a suitable controller operable by an operator standing on the platform 170, such controllers and 60 mountings being well known and not necessary of further illustration or description herein.

In some cases, when the skid is moved to pick up a load either from a platform or from a vehicle bed, it may be desirable to provide the buffer 65 69 above described at the end of the skid with one or more rollers, to further and more easily guide the load into the skid. In Figs. 17 and 18 is illustrated a roller 186, projecting through a suitable aperture in the buffer 69, the roller 186 rotating 70 on a short shaft 187, the ends of the shaft outwardly beyond the roller being, in the construction illustrated, welded to the inner side of the buffer 69.

It will be understood, of course, without further drawing or description to complicate this 75

disclosure, that the rollers 186, as well as the rollers 59-59 and 65-65, may if desired, be driven by power.

My invention is not limited to the exact details of construction illustrated and described. Many changes and modifications may be made within the spirit of my invention without sacrificing its advantages and within the scope of the appended claims.

I claim:

1. In a load transfer apparatus, a main frame, a body movably supported on the frame and adapted to carry a load, a truck movable on the frame, a rotary support for one end of the body on the frame, the truck being movable on the frame to a position adjacent to the opposite end of the body and comprising means operable to raise that end of the body from the frame and to support the body on the truck at that end and on the frame at the said one end, and the truck being movable to then move the body on its rotary support to dispose the said one end over a station, and a wheel support on the body to engage the station and to support said one end of the body independently of the rotary support. 25

2. In a load transfer apparatus, a main frame, a body movably supported on the frame and adapted to carry a load, a truck movable on the frame, a support for each end portion of the body on the frame, the truck being movable to positions adjacent either end of the body, and comprising means operable to raise the adjacent end of the body from the frame to cause the body to be supported on the truck at one end and on the frame at the other end, the truck being movable to move the body on its frame support to dispose the frame supported end over a station, and a support on each end of the body to engage the station and support the corresponding end of the body thereon independently of the frame support. 40

3. In a load transfer apparatus, a frame, a body adapted to support a load, a track-way and a wheel, one on the body and the other on the frame, the wheel engageable with the track way 45 to roll therealong, and movingly support the body, the track-way having a normal portion and an inclined portion, a truck movable on the frame and having means to engage and support the body at a point spaced from the track-way and 50 wheel supported portion of the body and movable to move the body to cause the wheel to roll down the track-way incline, and lower the adjacent portion of the body, a wheel support on the descending portion of the body engageable with a 55 station platform to support the body end independently of the wheel and track-way support.

4. In a load transfer mechanism, a frame, a track-way on the frame having a generally horizontal part and a declining portion, a load carrying body supported by a wheel on the track-way, means to move the body to roll it up and down the incline, and an abutment mechanism operable by the wheel upon the rolling onto the horizontal track-way portion to project an abutment in front of the wheel to prevent rolling thereof beyond the horizontal portion. 60

5. In a load transfer apparatus, a frame, a track-way at opposite end of the frame, the track-ways each having a horizontal portion and an inclined portion, a load carryable body supported by wheels on the track-ways, a truck movable on the frame, an abutment mechanism comprising an abutment in front of the wheels on the track-way to prevent movement of the body, the truck 70

75

- being movable on the frame and having automatic means to elevate one end of the body and remove the adjacent abutment and to lower the body and restore the abutment, and while the body is elevated the truck being movable on the frame to move the body therewith causing its wheel support to roll down the inclined track-way at the other end.
6. In a load transfer apparatus, a body comprising a load supporting floors, an apron mechanism at the end of the floor for engaging under a load on a station surface and for transferring it to the body floor, when the body floor is moved toward the load, the apron mechanism comprising an apron element having a downwardly inclined upper surface and hinged to the body, a roller mounted thereunder, rollable upon the load station surface, and a roller mounted thereon projecting upwardly above the inclined surface, and a roller supported at the hinging axis of the apron, and an opening between the apron and the end of the floor through which the end of a strip of flexible material may be projected downwardly, the body of which strip lies on the station surface and on the apron.
7. In a load transfer apparatus, a main frame, a load carryable body movable on the frame, rails on the frame, a truck movable on the rails, the truck supporting an elevator mechanism comprising an element movable upwardly to engage a portion of the body and elevate and support it, means for interlocking the element with the body to prevent relative displacement thereof when the body portion is supported on the element.
8. In a load transfer apparatus, a main frame, track-rails on the frame, a truck movable on the rails, a load body provided with wheels on its opposite end portions, trackways for the wheels, a pair of abutments projecting upwardly between the wheels, one engaging each wheel to normally lock the body against movement, an elevator on the truck, comprising an element movable upwardly to engage the body at one end portion and raise it from the track-way, the truck comprising means for removing the abutment at the elevated end, the truck being movable in one direction along the rails to move the body along its track-way support at the other end in one direction and to return it in the other direction, and after returning, the elevator being movable to lower the body to engage its wheel with the corresponding track-way and means operable by lowering of the wheel to restore the abutment.
9. In a load transfer apparatus, a body having a conveyor adapted to carry a load thereon, a frame, means comprising wheels and a trackway upon which the body is movably supported and guided on the frame, the trackway comprising an inclined portion by which an end portion of the body is caused to descend by movement of the body on the frame to cause a corresponding end portion of the conveyor to be positioned upon a load carrying station adjacent to a load thereon, and moving means for then moving the conveyor and body, the conveyor in a direction opposite to and at a speed commensurable with that of the body to effect progressive movement of the conveyor under the load and the transferring of the load from the station to and upon the conveyor.
10. In a load transfer apparatus, a body having a conveyor adapted to carry a load thereon, a frame, means comprising wheels and a trackway upon which the body is movably supported and guided on the frame, the trackway comprising an inclined portion by which an end portion of the body is caused to descend upon moving the body on the frame to cause a corresponding end portion of the conveyor to be positioned upon a load receiving station, moving means for then moving the conveyor and the body, the conveyor in the direction opposite to and at a speed commensurable with that of the body to effect progressive withdrawal of the conveyor from under a load thereon and the progressive transferring of the load from the body to the station.
11. In a load transfer apparatus, a body having a conveyor adapted to carry a load thereon, a frame, means comprising wheels and a trackway upon which the body is movably supported and guided, and upon which the body may hingingly move in vertical directions on a hinging axis, moving means for moving the conveyor and the body to position an end portion of the body over a station disposed at a different level from that of the hinging axis and to hingingly move the body to engage the end portion with the station at a point in front of a load on the station to cause the said end portion to be supported on the station and to move thereover toward the load, an apron hinged to the said body end portion and having a depending forward portion movably engaging and supported by the station in all hinged positions of the body, means for moving the conveyor in the direction opposite to that of the body and at a speed substantially less than that of the body whereby the apron forward portion may be progressively moved under the load and the load progressively transferred over the apron from the station to and upon the conveyor and the load concurrently packed by sliding frictional engagement of the underside of the load with the conveyor.
12. In a load transfer apparatus, a body having a conveyor adapted to carry a load, a frame, means comprising wheels and a trackway upon which the body is movably supported and guided on the frame, and upon which the body may hingingly move in vertical directions on a hinging axis, moving means for moving the conveyor and the body to position an end portion of the body over a station disposed at a different level from that of the hinging axis, and to hingingly move the body to engage the end portion with the station to cause the said end portion to be supported on the station and to move thereover, an apron hinged to the said body end portion and having a depending forward portion movably engaging and supported by the station in all hinged positions of the body, means for moving the conveyor in the opposite direction to that of the body and at a speed substantially greater than that of the body to effect the progressive withdrawal of the conveyor and apron from under a load carried by the conveyor and the progressive transferring of the load over the apron to and upon the load receiving station, and to effect concurrent packing of the load by the sliding frictional engagement of the underside of the load with the conveyor.
13. In a load transfer apparatus, a body having a conveyor adapted to carry a load thereon, a frame, means comprising wheels and a trackway upon which the body is movably supported and guided in opposite directions of movement of the frame, means for moving the conveyor and body to dispose either end portion of the body over one or another of opposite load stations, moving means for moving the conveyor in a direction opposite that of the body and at a speed commensurable with that of the body whereby the con-

veyor is progressively moved under a load on one station to progressively transfer the load from said one station to the body and the conveyor is progressively withdrawn from under the load to progressively transfer the load to said other station.

14. In a load transfer apparatus, a body having a conveyor adapted to carry a load thereon, a frame, means comprising wheels and a trackway upon which the body is movably supported and guided in opposite directions of movement on the frame, the trackway comprising inclined portions at opposite end portions of the frame by which, upon movement of the body in either direction, one end portion or the other of the body is caused to descend to cause a corresponding end portion of the conveyor to be positioned upon one or another of opposite load stations, moving means to move the body and the conveyor and in opposite directions and at a speed commensurable with each other whereby either one end of the conveyor may be progressively moved under a load at a loaded station to progressively transfer the load from the station to the conveyor and the other end of the conveyor is progressively withdrawn from under the load to progressively transfer the load from the conveyor to and upon the other station.

15. In a load transfer apparatus, a body having a conveyor adapted to carry a load thereon, a frame, means comprising wheels and a trackway upon which the body is movably supported and guided in opposite directions of movement on the frame, whereby opposite ends of the conveyor may be positioned upon oppositely disposed load stations, and moving means for moving the conveyor and the body in opposite directions whereby one end of the conveyor may either be progressively moved under a load at a loaded station and the load progressively transferred to and upon the conveyor and the other end of the conveyor may be placed over a receiving station and the conveyor progressively withdrawn from under the load and the load progressively transferred to the receiving station, and the moving means being arranged to move the conveyor when receiving the load at a speed substantially less than that of the conveyor to concurrently compact the load on the conveyor and to move the conveyor when discharging the load upon the receiving station at a speed substantially greater than that of the body to concurrently compact the discharged load on the receiving station.

16. In a load transfer apparatus, a body supporting a conveyor adapted to carry a load, a frame, means comprising wheels and a trackway upon which the body is movably supported and guided on the frame, means comprising frame wheels on the frame and a trackway upon which the frame and frame wheels are movably supported for movement transversely with respect to the said body movement, to dispose the body opposite to one or another of a plurality of load stations, said first named means comprising means upon which the body may hingingly move in vertical directions on a hinging axis, moving means for moving the conveyor and the body to position an end portion of the body over a station disposed at a different level from that of the hinging axis and to hingingly move the body to engage the end portion with the station at a point in front of a load on the station to cause the said end portion to be supported on the station and to move thereover, an apron hinged to the said body end portion and having a depending forward portion

movably engaging and supported by the station in all hinged positions of the body, means for moving the body toward the said load to progressively move the end of the body and apron forward portion under the load while concurrently moving the conveyor in the opposite direction to progressively transfer the load to and upon the conveyor and for moving the body and conveyor away from the station and, after traverse movement, toward another station to dispose the said end portion of the body over the said other station with the said end portion and apron forward portion movably engaged with the station and for then withdrawing the body while concurrently moving the conveyor in the direction opposite to that of the body movement to progressively transfer the load from the conveyor over the apron to the said other station.

17. In a load transfer apparatus, a body comprising a conveyor adapted to support a load, means at the end of the conveyor for engagement under a load on a station surface and for guiding the load while being transferred to the conveyor when the body is being moved under the load, said means comprising a flexible element in the form of a piece of fabric or the like on the station and upon which the load is disposed, and having a free end portion projecting from under the load and comprising an apron element having a rearward portion hinged to the body and separated therefrom by a transverse opening and having a downwardly inclined upper surface portion, and the forward portion thereof having rotary bearing means secured thereto and rollable upon the station surface, an upwardly open aperture in the upper surface portion of the apron, an upper roller supported upon bearing means under the upper surface portion, and the upper portion of the upper roller projecting upwardly through the aperture, and the free end of the flexible element overlapping the apron and upper roller and projecting downwardly through the said opening.

18. In a load transferring apparatus, a main frame, track rails on the frame, a truck movable to and fro on the rails, a load body provided with wheels on its opposite end portions, a trackway on the frame for the wheels on which the body may be moved to and fro, a pair of abutments projecting upwardly between the wheels, one engageable by each wheel to normally lock the body against movement, an elevator on the truck comprising an element movable upwardly to engage the body at either end portion thereof and to raise its corresponding wheel from the trackway to clear the corresponding abutment whereby the truck upon being moved may move the body therewith in either direction.

19. The apparatus described in claim 18 and in which the trackway has inclined portions by which, upon movement of the body by the truck, either end portion of the body opposite to the truck engaged end portion may descend to lower the end wheels of the body upon a load station.

20. In a load transfer apparatus, a body supporting a conveyor adapted to carry a load, a frame, means comprising wheels and a trackway upon which the body is movably supported and guided on the frame, means comprising frame wheels on the frame and a trackway upon which the frame and frame wheels are movably supported for movement of the frame transversely with respect to the body movement to dispose the body opposite to one or another of load stations, said first named means comprising means

upon which either end portion of the body may hingingly move in vertical directions on respective hinging axes, moving means for moving the conveyor and the body to position one end portion 5 of the body over a station disposed at a different level from that of the hinging axes and into moving engagement with the station at a point in front of a load on the station to cause the said end portion to be supported on the station and 10 to move thereover, an apron hinged to the said body end portion and having a depending forward portion movably engaging and supported by the station in all hinged positions of the body, means for moving the body toward the said load 15 15 to progressively move the said end portion and apron forward portion under the load while concurrently moving the conveyor in the opposite direction to progressively transfer the load to and upon the conveyor and for moving the body and 20 20 conveyor away from the station and, after a transverse movement, toward another station to dispose the other end portion of the body over the said other station and with the other end portion of the body movably engaged with the other 25 station, another apron hinged to the said other body end portion and having a forward portion

movably engaged with the said other station, and for then withdrawing the body and conveyor and apron while concurrently moving the conveyor in the direction opposite to that of the body movement to progressively transfer the load from the 5 conveyor over the apron to said other station.

21. In a load transferring apparatus, a body supporting a conveyor adapted to carrying a load thereon, a frame, means comprising wheels and a trackway upon which the body is movably supported on the frame and upon which the body may hingingly move in vertical directions on a hinging axis, moving means for moving the conveyor and the body to position an end portion of the body over a station disposed at a different 10 level from that of the hinging axis, and to hingingly move the body to engage the end portion of the body with the station to cause the said end portion to be supported on the station and to move thereover, an apron hinged to the said body 15 end portion and having a depending forward portion movably engaging and supported by the station in all hinged positions of the body and constituting an extension of the conveyor, and means for moving the conveyor.

JAMES FRANKLIN MAINE.
